UNITED STATES PATENT OFFICE.

MOSES F. CARR, OF LEXINGTON, MASSACHUSETTS, ASSIGNOR, BY MESNE ASSIGNMENTS, TO THE BASSICK MANUFACTURING COMPANY, OF CHICAGO, ILLINOIS, A CORPORATION OF DELAWARE.

LUBRICATING NIPPLE AND CAP THEREFOR.

Application filed February 1, 1923. Serial No. 616,345.

This invention pertains to improvements in lubricating nipples and caps therefor. The construction herein illustrated is a modification of that shown in my co-pending application Serial No. 616,344, filed here-with.

In the drawings, which show a preferred form of one embodiment of my invention:

Figure 1 is the side elevation of a lubricating nipple attached to a part to be lubricated and protected by a cap;

Fig. 2 is a section on the line 2—2 of Fig. 1, being partly in elevation;

Fig. 3 is a section on the line 3—3 of Fig. 15 2; and

Fig. 4 is a section on the line 4—4 of Fig. 2, being partly in elevation.

Referring to the drawings and to the preferred form of my invention selected for 20 illustrative purposes, I have shown a lubricant-receiving nipple of the character described in my co-pending application above referred to, containing a passage therethrough for the lubricant, a spring in the 25 passage and a check ball 5 closing the opening at the lubricant-receiving end of the nipple. The center portion of the nipple has a steep pitch thread 6 for engagement with a corresponding thread on the interior 30 of the nozzle of a lubricant delivering gun.

At one side of this steep pitch thread is a finer pitch thread 7 adapted to be screwed into the part to be lubricated 8. At the other side of the steep pitch thread is a 35 cylindrical portion 9 for engagement by a sealing element of the hat washer type. Between the cylindrical portion 9 and the steep pitch thread 6, I have provided a neck 10 to retain a dust cap which is preferably 40 formed of two pieces of sheet metal, the first a cover portion 11 flanged over and about a skirt portion 12 covering the remainder of the cylindrical portion of the nipple and the central portion thereof having a steep 45 pitch thread. The connection between the parts 11, 12 is preferably such as to provide a convenient finger hold 13.

In the skirt portion 12 is preferably provided a depression 14 adapted to engage in

the neck 10 with resilient pressure to prevent rattling of the nipple. This depression 14 and, if desired, a shoulder 15 are preferably so located as to prevent the top closure 11 of the cap from coming into contact with the ball 5. The skirt portion 12 is preferably of such diameter that when split for a portion of its length at 16, it will closely embrace and press against the exterior of the threaded portion 6, while providing a minimum of opening at 16 through which dust 50 might enter.

While I have shown and described a preferred embodiment of my invention, it will be understood that I have done so for purposes of clarification and not for purposes of limitation. My invention is best defined in the following claims.

I claim—

1. A dust cap presenting a resilient skirt portion for enclosing the coupling means 70 presented by a nipple to exclude dust and dirt therefrom, said skirt presenting at one side a slit to provide resiliency and, at a point adjacent said slit, a struck-in depression for resilient engagement with a neck on 75 the lubricant-receiving nipple.

2. A dust cap presenting a resilient skirt portion generally tubular in shape to provide means for covering the coupling means 80 of a lubricant-receiving nipple to exclude dust and dirt therefrom and presenting at one side a slit to provide resiliency and a struck-in depression located substantially midway between the ends of the cap for 85 resilient engagement with a neck on the lubricant-receiving nipple.

3. A dust cap for a lubricant-receiving nipple presenting a cylindrical skirt portion for resiliently embracing and covering a threaded portion of a nipple to exclude dust 90 and dirt therefrom, said skirt portion being slit to provide resiliency and presenting a struck in depression in the skirt portion for resilient engagement with a neck on the lubricant-receiving nipple. 95

In testimony whereof, I have signed my name to this specification.

MOSES F. CARR.
